V-TRUSS

Walter F. Sheehan, St. Louis, Mo.

Application July 10, 1939, Serial No. 283,633

12 Claims. (Cl. 72—70)

This invention relates to V-trusses designed and adapted for use in concrete floors to reinforce, strengthen, and support the concrete floor structure.

Objects of the invention are to produce a light-weight V-shaped truss having a pair of spaced webs made of sheet steel; to provide such a truss in which the webs have openings therethrough formed by stamping or cutting out portions of the webs to permit the concrete to enter between the two webs of the truss; to provide a truss formed of sheet steel and including two downwardly converging webs united at their upper edges by an integral top member having openings permitting the concrete to enter and fill the space between the downwardly converging webs of the truss; to provide a light-weight sheet metal truss including downwardly extended webs united by a top portion having integral therewith tongues extending downwardly between the webs and holding them in proper spaced relationship, and provided with openings into and through which the concrete may pass to form integral connection with the concrete on opposite sides of said tongues; to provide at the lower chord of the truss an appropriately formed bar located between the webs of the truss and flush with the bottom edges thereof to add additional strength thereto when the truss is in tension in the floor; and to provide a light-weight sheet metal truss having downwardly extended webs which may be spaced apart by any appropriate means and attached along their upper edges or not, as desired.

Another object of the invention is to provide a truss of the character mentioned having flanges in connection with the lower edges of the webs and the strengthening bar to support the spanning member or void-filler upon which the concrete is poured and which supports the concrete until the concrete hardens, and which thereafter remains in attached engagement with the concrete.

Other objects of the invention will be apparent from the following description, reference being made to the annexed drawings, in which—

Fig. 1 is a plan view of a portion of a concrete floor having my improved truss embodied therein.

Fig. 2 is a vertical sectional view of the floor along the line 2—2 of Fig. 1.

Fig. 3 is a vertical sectional view of the floor along the line 3—3 of Fig. 1.

Fig. 4 is a vertical sectional view of the floor along the line 4—4 of Fig. 1.

Fig. 5 is a plan view of a portion of a concrete

floor embodying another form of my improved truss.

Fig. 6 is a vertical sectional view of the floor along the line 6—6 of Fig. 5.

Fig. 7 is a vertical sectional view of the floor along the line 7—7 of Fig. 5.

Fig. 8 is a vertical sectional view along the line 8—8 of Fig. 5.

The truss shown in Figs. 1 to 4, inclusive, is made of light-weight sheet steel bent to form a pair of spaced webs 1 and 2 integrally united at their upper edges by a top portion 3. Series of openings 4, 5 and 6 are formed through each web by stamping or cutting out portions of the webs to permit the concrete to enter between the two webs of the truss. The top portion 3 is cut or stamped to form a series of tongues 7 which are bent downwardly between the webs 1 and 2 and form braces or spacers therefor holding the truss webs 1 and 2 in approximately uniform spaced relationship throughout their length. Each of the tongues 7 is also stamped or cut to form an opening 8 in the upper and wider portion thereof through which the concrete may pass to opposite sides of the tongue to form integral connection with the mass of concrete at each side thereof.

In this form of the invention, the webs 1 and 2 converge downwardly and the tongues 7 are of tapered shape conforming to the desired space between the webs 1 and 2. When the tongues 7 are bent downwardly, openings 9 are thereby formed in the top portion 3 and, if required or desired, concrete may be poured through these openings 9 into the space between the webs 1 and 2.

In this form of the invention, an appropriately shaped bar 10 is welded or otherwise secured between the webs 1 and 2 of the truss and flush with the bottom edges thereof to provide additional strength therefor when the truss is under tension in the floor. A flange 11 attached to the bar 10 extends beyond the sides of the webs 1 and 2 and constitutes a support for the spanning member or void-filler 12 upon which the concrete is poured and which supports the concrete until the concrete hardens, and thereafter remains in attached engagement with the concrete, affording a finished under-surface for the floor.

Figs. 5 to 8 illustrate a modified form of the invention. This truss is also made of light-weight sheet steel which is bent to form a pair of spaced webs 13 and 14 and a top portion 15 integrally connected with the upper edges of the

webs. Series of openings 16, 17 and 18 are stamped or cut into the webs to permit concrete to enter between the two webs of the truss and form a mass of concrete within the truss integrally united with the concrete between the respective trusses. The top portion 15 is cut or stamped to form a series of tongues 19 which are extended downwardly between the webs 13 and 14 to form braces or spacers for the webs, holding them in approximately uniform spaced relationship throughout their length. These tongues are formed with openings 20 in their upper portions through which the concrete may pass to opposite sides of the tongues and form integral connection with the masses of concrete 15 at the sides thereof. When the tongues 19 are bent downwardly, openings 21 are formed through the top portions 15 through which concrete may be poured if desired or required. The webs 13 and 14 converge downwardly and the tongues 19 are of tapered shape, conforming to the desired space between said webs.

In this form of the invention, a T-bar is used instead of the bar 10 and the flange member 11. The stem 22 of the T-bar which is welded to said webs is extended upwardly between the lower margins of the webs 13 and 14, and the head 23 of said bar provides flanges to support a spanning member or void-filler 24 upon which the concrete is poured and which supports the concrete until the concrete hardens, and thereafter remains in attached engagement with the concrete to provide a finished under-surface for the floor.

In both forms of the invention, the concrete 25 is shown filling the space between trusses and also filling the trusses between the webs thereof. In Fig. 4, the tongues 7 cross the openings 6 and, in Fig. 7, the tongues 19 cross the openings 18. This assures that the concrete at opposite sides of the tongues within the trusses will be integrally united and also that the concrete within the trusses and at opposite sides of the tongues will be integrally united with the masses of concrete at the sides of the trusses. The remaining series of openings in the truss webs assure that the spaces between the webs of the trusses will be filled with concrete and integrally united with the exterior masses of concrete.

From the foregoing, it is apparent that this invention attains all of its intended objects and purposes efficiently, economically and satisfactorily. The trusses are of light weight. The webs may be formed otherwise than in V-shape when desired, and the bars 10 and supporting flange members 11 may be of different shapes, as may the T-bars shown in Fig. 8.

I contemplate other variations in the form and construction of these improved trusses, and do not restrict myself otherwise than as defined by the appended claims.

I claim:

1. A truss for use in concrete floor construction comprising a pair of longitudinal downwardly converging metallic webs having openings therethrough and connected together at their upper edges in spaced relationship, and a series of spacers spanning the space between and having their edges engaging the inner sides of and holding said webs in spaced relationship.

2. A truss for use in concrete floor construction comprising a pair of longitudinal flat downwardly converging metallic webs having openings therethrough, an integral top portion connecting

and holding the upper edges of said webs in spaced relationship and having openings therethrough, and a series of spacers integral with said top portion and extending downwardly and spanning the space between and having their edges engaging the inner sides of and holding said webs in spaced relationship.

3. A truss for use in concrete floor construction comprising a pair of downwardly converging webs having openings therethrough, a top portion integrally connecting and holding the upper portions of said webs in spaced relationship and having openings therethrough, and a series of spacers connected with said top portion and extending downwardly and spanning the space between and having their edges engaging the inner sides of and holding said webs in spaced relationship.

4. A sheet steel truss for use in concrete floor construction comprising a section of sheet metal including a pair of flat downwardly extended webs having openings therethrough and a top portion integrally connecting and holding the upper portions of said webs spaced apart, and a series of spacers spanning the space between and having their opposite edges engaging the inner sides of and holding said webs in spaced relationship.

5. A truss for use in concrete floor construction comprising a pair of longitudinal flat sheet metal webs having openings therethrough, and a series of spacers spanning the space between and each having its opposite edges engaging the inner sides of and holding said webs in spaced relationship downwardly from their upper edges extending across certain of said openings through said webs.

6. A truss for use in concrete floor construction comprising a pair of longitudinal flat sheet metal webs having openings therethrough, an integral top portion connecting and holding the upper edges of said webs in spaced relationship and having a longitudinal series of holes therethrough, and a reinforcing element secured between the lower margins of said webs.

7. A truss for use in concrete floor construction comprising a pair of flat sheet metal webs connected together at longitudinally spaced intervals along their upper edges in laterally spaced relationship, and a reinforcing element secured between the lower margins of said webs.

8. A truss for use in concrete floor construction comprising a pair of flat sheet metal webs, a series of spacers spanning the space between and each having its opposite edges engaging the inner sides of and holding said webs in spaced relationship, and a reinforcing element secured between the lower margins of said webs below said spacers.

9. A reinforcing concrete floor construction comprising trusses, each including a pair of longitudinal flat sheet metal webs, spacers between and each having its opposite edges engaging the inner sides of and holding the webs of each truss in spaced relationship, a reinforcing element secured between the lower margins of the webs of each truss and below said spacers, a flange member attached to and supported by each of said reinforcing elements and extending laterally beyond said webs, and a spanning member or void-filler supported by said flange members on adjacent trusses.

10. A reinforcing concrete floor construction comprising trusses, each including a pair of longitudinal flat sheet metal webs, spacers between

and each having its opposite edges engaging the inner sides of and holding the webs of each truss in spaced relationship, a reinforcing element secured between the lower margins of the webs of each truss and below said spacers, a flange member attached to and supported by each of said reinforcing elements and extending laterally beyond said webs, a spanning member or void-filler supported by said flange members on adjacent trusses, and concrete filling the spaces between said trusses above said member or filler.

11. A reinforcing concrete floor construction comprising spaced sheet metal trusses, each including a pair of spaced flat webs having openings therethrough, spacers between and each having its opposite edges engaging the inner sides of and holding the webs of each truss in spaced relationship, a reinforcing member secured between the lower margins of the webs of each truss

and below said spacers, a flange member attached to and supported by each reinforcing element and extending laterally beyond the webs of the adjacent truss, an arched spanning or void-filler member between each pair of trusses supported by said flange members, and concrete filling the space between said trusses and also filling the spaces between the webs of the trusses in integral connection throughout.

10 12. A V-truss for use in concrete floor construction comprising a pair of downwardly converging flat metallic webs having openings therethrough, spacers between and each having its opposite edges engaging and holding said webs in spaced relationship, a reinforcing member secured between the lower margins of said webs below said spacers, and means attached thereto for supporting a spanning or void-filler member.

WALTER F. SHEEHAN.
